United States Patent Office

Des. 213,759
Patented Apr. 8, 1969

213,759

SEWING TRAY

Robert Z. Lerner, Brookville, N.Y., assignor to Lerner Manufacturing Co., Inc., Melville, N.Y., a corporation of New York

Filed May 2, 1968, Ser. No. 11,747

Term of patent 7 years

Int. Cl. D7—01

U.S. Cl. D3—19

FIG. 1

FIG. 4

FIG. 2

FIG. 3

FIG. 1 is a perspective view of a sewing tray embodying my new design;

FIG. 2 is a top plan view thereof;

FIG. 3 is a side elevational view thereof; and

FIG. 4 is an end elevational view thereof.

The essential features of the design reside in the portions shown in full lines.

I claim:

The ornamental design for a sewing tray, as shown and described.
